UNITED STATES PATENT OFFICE.

ROBERT T. MEYER, OF CANTON, OHIO.

SUCTION SEPARATOR.

Application filed July 28, 1919. Serial No. 313,845.

To all whom it may concern:

Be it known that I, ROBERT T. MEYER, a citizen of the United States, residing at Canton, in the county of Stark and State of Ohio, have invented a new and useful Suction Separator, of which the following is a specification.

This invention relates to improvements in suction separators, the object being to construct a separator of this class in which the maximum amount of agitation can be given to the material being separated, thus causing it to be more readily acted upon by the current of air drawn through the separating cylinders.

Another object is to construct a separator of this class with double rotating cylinders through which the air suction is drawn, thus agitating the material being separated constantly, which permits the air being sucked through the said cylinders to more quickly separate the material and enabling the machine to separate a greater volume of material in a given length of time.

With these objects in view the invention consists in the novel construction and arrangement of parts, hereinafter described, illustrated in the accompanying drawings, and particularly pointed out in the appended claim, it being understood that various changes in the form, proportions, size and minor details of construction may be made within the scope of the appended claim, without departing from the spirit or sacrificing any of the advantages of the invention.

In the drawings:

Figure 1 is a side elevation of my separator with the horizontal bars upon the near side broken away to disclose the rotating cylinders and mechanism therefor.

Fig. 2 is an enlarged longitudinal sectional view through the feed opening and center terminals of the rotating cylinders.

Fig. 3 is a front elevation of my machine.

Fig. 4 is a section through one of the cylinders at the point 4—4, on Fig 1.

Similar numerals of reference indicate corresponding parts throughout the several figures of the drawings.

At 1 I have indicated generally a suitable frame formed of channel bars or similar material and properly braced to carry the mechanism of my separator. A fan shaft 2 upon which is mounted a fan carried in a fan casing 4 is adapted to be driven by a belt

5 running to a suitable source of power, not shown, the fan being arranged within the said casing to create a suction through the pipe 6 and discharge the air sucked in 60 through the outlet 7. A separating chamber 8 is connected to the suction pipe 6 and has located therein a baffle plate 9 for the purpose hereinafter to be described. The inclined face 10 of the separating chamber 65 leads to a discharge door 11 located in the extreme lower corner of the chamber. The chamber 8 is preferably made of sheet metal and connected to one end of the framework 1 in any convenient and well known 70 manner. Mounted at the inside upper corner of the chamber 8 is a casting 12 with a substantially right angular passage therethrough, one end of which passage opens into the said chamber 8. Secured to oppositely extending lugs 14 upon the said casting 75 is a support member 15, the other end of which is secured to a casting 16, which is mounted to slide between the guide bars 17 at the front end of the frame. A forwardly 80 projecting flange 18 preferably formed integral with the casting 16 at its upper edge has a centrally located aperture therethrough in which is mounted to rotate one end of the adjusting screw 19, which adjusting screw 85 extends upwardly and through the end cross member of the frame and has threaded thereon a hand wheel 20, by the rotation of which the adjusting screw can be raised or lowered to raise or lower the casting 16. At 90 the lower end of the casting 16 is a forwardly projecting flange 21, which extends between the guide bars 17 and is designed to act as a guide for the said casting when the same is raised or lowered. The front end of 95 the casting 12 forms a bearing for the upper end of the cylinder 22, the lower end of which carries a collar 24, the said collar having an annular flange 25, which fits about an annular flange 26 formed 100 upon a casting 27 mounted upon the support bar 15. An annular flange 28 substantially similar to the flange 26 extends from the opposite side of the casting 27 and is designed to form a bearing for the annular 105 flange 29 formed preferably integral with the collar 30, said collar 30 being attached to the second cylinder 31, the lower end of the second cylinder 31 being mounted to rotate within the casting 16.

A neck 32 extends upwardly from the casting 27 and receives the lower end of the

feed pipe 34 which leads from a hopper 35 mounted upon the top of the frame work. A lug 36 formed upon the casting 12 constitutes one bearing for a drive shaft 37, the other bearing for the said shaft being formed in the lug 38 upon the casting 16, and carried by the said shaft and adapted to rotate therewith are pinions 39 and 40 which mesh with gears 41 and 42 respectively, the gear 41 being secured about the cylinder 22 and the gear 42 being secured about the cylinder 31. The upper end of the shaft 37 has secured thereto a beveled pinion 44 which meshes with a second beveled pinion 45 keyed to a shaft 46, which shaft is mounted in suitable bearings secured to the frame work. The shaft 46 is rotated from any desired source of power preferably by belt and pulley, but it will be understood that any kind of gear may be used to transmit power to said shaft. The rotation of the shaft 46 will cause the shaft 37 to be rotated by the meshing of the beveled gears 44 and 45. The rotation of the shaft 37 will therefore cause the cylinders 22 and 31 to be rotated by the meshing of the pinions 39 and 40 with the gears 41 and 42, respectively. Located in the suction pipe 6 is a sliding valve 50, which is arranged to be operated through the rod 51, the screw threaded end of which carries a hand wheel 52. A substantially similar rod 54 having a hand wheel 55 upon its threaded forward end is designed to operate a feed regulator 56 located in the feed pipe 34 leading from the hopper 35 to the casting 27. Within the cylinders 22 and 31 and extending longitudinally therethrough is a plurality of agitator vanes 57 which are designed to tumble the material being separated to thus enable the air sucked through to more efficiently act upon the particles of matter.

The operation of my device will be as follows: We will assume that the separator is to be employed for the purpose of separating metal from ore. The fan within the casing 4 is set in motion to create a suction through the pipe 6 and chamber 8 and by virtue of the passage in the casting 12 connecting the cylinders with the said chamber 8, the suction created by the fan will draw air through the cylinders 22 and 31, from the lower or open end of the cylinder 31 thus forming a suction the entire length of both cylinders. The pulverized ore containing particles of the metal is now fed in through the hopper 35 and descends through the feed pipe 34 into the casting 27 through the neck 32 thereof. The hand wheel 52 is now rotated to adjust the sliding valve 50 in the suction pipe 6 to draw the exact amount of air necessary to create the

proper suction through the rotating cylinders 22 and 31 to suck the particles of rock upwardly and through the cylinder 22. The particles of metal mixed with the said pulverized rock being of greater specific gravity than the rock will not be drawn through the cylinder 22 by this suction of air but falling into the interior of the casting 27 will fall downwardly and into the rotating cylinder 31, finally emerging at the lower or open end of the cylinder 31 where a suitable receptacle is placed to receive them. The particles of crushed rock meanwhile are being carried upwardly through the rotating cylinder 22 and are kept constantly agitated by being carried upwardly upon the vanes 57 as the cylinder 22 rotates and falling by gravity as the surface of the vanes upon which they are carried is tilted downwardly. The particles of rock are thus constantly being carried up one side of the cylinder and dropped out into the air current, eventually arriving at the upper end of the cylinder and passing through the passage in the casting 12 and thence falling into the chamber 8. The baffle plate 9 in the chamber will force the suction to travel downwardly at this point toward the inclined bottom 10 of the chamber 8, and as the particles of rock are drawn into the chamber 8 from the exit of the casting 12 they will be sucked down and slide from the inclined surface 10 outwardly and through the exit door 11. It is obvious that when ore of a different character is to be separated the valve 50 can be adjusted to admit of a greater or less suction force as the case may require to properly suck the particles of rock from the particles of metal. It will also be understood that my separator is adapted to be used for a variety of other purposes than separating ore, such for instance as separating seeds or the like.

Having fully described my invention what I claim as new and desire to secure by Letters Patent, is:

In a separator of the character described, a frame, a casting supported upon said frame having an inclined passage therethrough and oppositely disposed, inclined flanges on its outer faces, a cylinder mounted to rotate within said frame, one end of said cylinder being journaled upon one of said oppositely extending flanges, a second cylinder mounted to rotate within said frame and one of the ends of the said second cylinder being journaled to rotate upon the other of said oppositely extending flanges, both of said cylinders communicating through the inclined passage in the said casting.

In testimony that I claim the above, I have hereunto subscribed my name.

ROBERT T. MEYER.
